UNITED STATES PATENT OFFICE.

ARTHUR M. HAIGHT, OF JACKSON, MICHIGAN.

SIGNAL LOCK FOR AUTOMOBILES.

Application filed March 8, 1920. Serial No. 364,275.

To all whom it may concern:

Be it known that I, ARTHUR M. HAIGHT, a citizen of the United States, residing at Jackson, in the county of Jackson and State of Michigan, have invented new and useful Improvements in Signal Locks for Automobiles, of which the following is a specification.

The object of my present sole invention is 10 the provision of any efficient lock in the ignition circuit of an automobile and designed in one position to complete the circuit including the spark plug or plugs and in another position to interrupt the said circuit and complete the circuit containing a 15 horn or other audible signal so that when the usual manually operated switch on the instrument board is closed the audible signal will be sounded and bystanders will be apprised of the fact that an unauthorized attempt is being made to move the automobile.

To the attainment of the foregoing the invention consists in the improvement as herein-after described and definitely claimed.

25 In the accompanying drawings hereby made a part hereof:

Figure 1 is a diagrammatic view illustrative of the preferred circuit system in which my novel lock is arranged.

30 Figure 2 is an enlarged rear elevation of the lock and showing the same in unlocked position—i. e., in position to assure the passage of current to the electrodes of a spark plug when the manually operated switch is closed.

Figure 3 is a similar view with the lock in position to preclude the supply of current to a spark plug when the manually operated switch is closed.

40 Figure 4 is an elevation of the lock taken at right angles to Figures 2 and 3.

Figure 5 is an elevation showing the body of the lock with the commutator discs removed.

45 Figure 6 is a detail edge elevation illustrative of the circuit closing members for completing the circuit containing the spark plug or plugs.

Figure 7 is a detail elevation of the 50 ratchet disc.

Figure 8 is a detail elevation of the outer combination disc.

Figure 9 is a detail edge view of the outer combination disc.

55 Figure 10 is a detail elevation of the intermediate combination disc.

Figure 11 is a detail edge view of the intermediate combination disc.

Figure 12 is a detail elevation of the inner combination disc. 60

Figure 13 is a detail edge view of the inner combination disc.

Figure 14 is a detail sectional view taken on line 14—14 of Figure 12.

Figure 15 is a detail view of one of the 65 spacing elements.

Similar numerals of reference designate corresponding parts in all the views of the drawings.

The body 1 of my novel lock is formed of 70 fiber or other insulating material, and is preferably circular in form and provided on its periphery with binding posts 2, 3 and 4; the post 2 being electrically connected with the manual switch, indicated by 5 in Figure 75 1, the post 3 being similarly connected with the horn, indicated by 6 in Figure 1, and the post 4 being electrically connected with the spark plugs, indicated by 7 in Figure 1 while the usual electric button for operating 80 the horn is designated by 7' in Fig. 1.

Extending centrally through the lock body 1 is a metallic sleeve 7" forming a bearing for a spindle 8 on the forward portion of which is a preferably knurled handle 9. 85

Fixed to the spindle 8 at the opposite sides of the body 1, with reference to the handle 9 is a ratchet disc 10. Loosely mounted on and revoluble about the sleeve 7" and interposed between the rear side of 90 the body 1 and the ratchet disc 10 are three combination discs 11. Each disc 10 is provided with a series of threaded openings 11'. A plurality of threaded lugs 11" are adjusted in the threaded openings in each 95 disc to suit the combination desired for the lock. The lug in the outer disc 11 extends through an opening 10' in the disc 10 and cooperates with the other lugs to cause the discs 11 to rotate upon the movement of the 100 handle 9. A plurality of circular spacing elements 11" surround the sleeve 7" upon opposite sides of each disc. A spring 11^b is secured to the rear side of the body and serves as a stop for one of the lugs 11' carried by the inner disc 11. These discs 11 105 may be of the construction and relative arrangement illustrated or of any other construction and relative arrangement compatible with the purpose of my invention and 110 appropriate to the scheme of the invention that contemplates the working of a combina-

tion with a view to bringing into coincidence the enlarged V-shaped peripheral notches 12 in the discs 11.

Connected to the rear side of the body 1 and bearing against the peripheries of the two discs 11 nearest the body is a pair of spring pressed shoes 13 the function of which is to prevent too free movement of said discs.

10. Electrically connected with the binding post 3 is a resilient detent 14 that is designed to cooperate with the ratchet disc 10 and serves to produce audible clicks incidental to the working of the lock so that the operator 15 can tell when he is following the prescribed combination for the unlocking of the lock; it being understood in this connection that when the lock is unlocked for the supply of current to the spark plug or plugs it is simply necessary to turn the spindle 8 in either direction in order to lock the lock and thereby interrupt the electrical connection to the spark plug or plugs.

Electrically connected with the binding 25 posts 2 is a swinging circuit closing element 20 that is normally pressed inwardly by a spring 21. The said element 20 has a major portion 21' close against the rear side of the body 1 and a minor portion 22 that is disposed at right angles to the major portion and is provided at its free end with a toe 23 engaging the periphery of the discs to complete the circuit to the horn and designed to enter the notches when said notches are in 30 registration thereby breaking the circuit to the horn.

As shown in Figure 6 the body 1 is shoudered at 24, and connected to the rear side of the body and reaching over the said shouder is a circuit closing element 25, complementary to the element 20.

It will be readily manifest from the foregoing that when my novel lock is locked as shown in Figure 3 the members 20 and 25 are separated, and current from the battery will pass through the minor portion 22 and toe 23 to the discs 11 and thence to the detent 14 and post 3 to the horn. Therefore, when the manual switch 5 is closed in the attempt to start the motor, the circuit containing the horn 6 will be completed and the horn will be sounded to put bystanders on

notice to the effect that an unauthorized attempt is being made to move the automobile. When however the lock is unlocked as shown in Figure 2 so that the notches 12 of the commutator discs are in coincidence, and the toe 23 of member 20 is adapted to enter said notches, the member 20 will be in contact with the member 25 with the result that closing of the switch 5 will be attended by the supply of current to the spark plug or plugs.

It will be apparent from the foregoing that notwithstanding the capacity of function of my novel lock, the same is compact and simple and is free from delicate parts such as are likely to get out of order after a short period of use. It will also be apparent that the lock may be so made as to enhance 70 rather than detract from the finished appearance of an automobile interior.

Having described my invention, what I claim and desire to secure by Letters-Patent is:

A lock of the character described comprising a body, a sleeve extending through said body, a spindle mounted in said sleeve, a knurled handle secured to one end of said spindle, a plurality of combination discs 80 loosely mounted on said sleeve having enlarged V-shaped peripheral notches and provided with threaded openings, a plurality of adjustably threaded lugs engaging the threaded openings in said discs, a spring secured to said body and adapted to engage one of said lugs, a ratchet disc removably secured to said spindle adjacent to the opposite end thereof and provided with an opening receiving one of said lugs, a resilient detent 90 engaging the periphery of said ratchet disc, a contact member, a plurality of spring influenced shoes engaging said discs, a swinging spring influenced electric contact member having a major portion adapted to engage said contact member aforesaid and having a minor portion provided with a toe adapted to engage the periphery of said discs and to enter the V-shaped notches in said discs, as and for the purpose specified. 100

In testimony whereof I affix my signature.

ARTHUR M. HAIGHT.
